UNITED STATES PATENT OFFICE.

WILLIAM H. SAUVAGE, OF FLUSHING, NEW YORK, ASSIGNOR TO GOULD COUPLER COMPANY, A CORPORATION OF NEW YORK.

SLACK-ADJUSTER.

1,227,955.

Specification of Letters Patent. Patented May 29, 1917.

Application filed January 25, 1916. Serial No. 74,191.

To all whom it may concern:

Be it known that I, WILLIAM H. SAUVAGE, citizen of the United States and resident of Flushing, in the county of Queens and State 5 of New York, have invented certain new and useful Improvements in Slack-Adjusters, of which the following is a specification.

This invention relates to slack adjusters for the brake rigging of railway cars, and in 10 its more intense aspect to automatic slack adjusters particularly adapted for association with the brake rigging of car trucks.

One of the objects of the present invention is to provide a simple and practical 15 automatic slack adjuster mechanism which will be reliable and efficient in use and operation. A further object is to provide a slack adjuster mechanism of the above general character having relatively few parts 20 which are not likely to get out of order and will be cheap to manufacture and install.

Other objects will be in part obvious from the annexed drawings and in part indicated in connection therewith by the following 25 analysis of this invention.

This invention accordingly consists in the features of construction, combination of parts and in the unique relation of the members and in the relative proportioning and 30 disposition thereof, all as more completely outlined herein.

To enable others skilled in the art so fully to comprehend the underlying features thereof that they may embody the same by 35 the numerous modifications in structure and relation contemplated by this invention, drawings depicting a preferred form have been annexed as a part of this disclosure, and in such drawings, like characters of ref- 40 erence denote corresponding parts throughout all the views, in which—

Figure 1 is a side elevation showing such parts of a truck and associated brake rigging, partly in section, as are necessary to 45 fully understand the present invention.

Figs. 2 and 3 are detail views.

Fig. 4 is a detail vertical sectional view of the permanent take up and holding means.

Referring now to the drawings in detail, 50 and more particularly to Fig. 1, 5 denotes a truck bolster to each side of which are pivotally supported hangers 6 carrying brake beam struts 7 connected with brake beams 8 provided with the usual heads and shoes.

Associated with these struts are live and 55 dead levers 10 and 11 respectively, the dead lever being hung at its upper end 12 to an adjustable hanger while the corresponding end of the live lever is connected to a pull rod 13 connected with the usual actuating 60 mechanism (not shown). The lower ends of these levers are connected by a two part telescopic push rod comprising an internal or smaller member 14 and an outer casing 15.

Within a housing 16 formed in the member 15 are positioned one or more substantially rectangular dogs 17 having holes therein through which the rod 14 passes and normally held in canted position by a spiral spring 18 in such a manner as to prevent 65 normally an inward telescopic movement of the parts yet permit free expansion thereof as may be necessary to take up and permanently hold the excess travel or slack due to wear of the parts.

This permanent take up or positive clutch mechanism is connected with an adjusting rod 20 mounted upon and connecting depending lugs 21 on each of the brake beams. At one end there is provided a lost motion 70 connection including a short slot 22 through which passes a pin 22' adapted to maintain predetermined brake shoe clearance, while at the opposite end is a friction take up device 23 shown in detail in Fig. 2 adapted 75 to travel along a slot 24. This friction or temporary take up device may be of any desired character, but preferably comprises a pair of spring actuated or yieldingly held members engaging the opposite sides of the 80 adjusting rod 20. One end of the adjusting rod is shown more clearly in Fig. 2 and comprises a socket 25 within which fits a half ball washer 26, with a flaring central 85 opening fitting about a stud 27 adapted to permit relative rocking movement of the adjusting rod 20 about its longitudinal axis. A volute spring 28 engages one side of the 90 hanger 21 and reacts against the head 29 of the stud 27 thereby to yieldingly grip 100 the rod 20 between the washers carried by the stud on the opposite side of the hanger.

The other end is supported in a similar manner as far as the universal joint connection is concerned, for in operation there is more or less rocking and swaying of the parts with respect to each other, and in order to prevent wear of either the hangers 21 or the 105

adjusting rod 20 these half ball hangers are found to be particularly desirable.

In order to restore the parts to normal position on release of the brakes a return spring 30 is connected with the central part of the live lever and the opposite brake beam substantially as shown.

The device operates in substantially the following manner: Application of the 10 brakes causes a movement of the upper end of the live lever toward the right which will react through the push rod 15 upon the dead lever 11 and carry the brake shoes into engagement with the peripheries of the wheels. If excess travel takes place 15 above that allowed for by the lost motion slot 22 there will be a relative slipping of the yielding friction take up device 23 along the slot 24 an amount corresponding to this excess travel. On release of the brakes, the 20 spring 30 tends to restore the parts to normal position, and after the brake shoes have first dropped away from the peripheries of the wheel, as permitted by the lost motion slot 22, further movement of the brake beams relatively toward each other will be 25 prevented until the telescopic push rod has been actuated to permanently take up and hold the excess travel by being automatically extended an amount equal thereto.

It is thus seen that the present invention 30 provides a simple and practical take up device for permanently absorbing the excess travel of brake rigging due to wear of the 35 parts. The device is simple and practical in construction and operation, and is believed to accomplish, among others, all of the objects and advantages above set forth.

Without further analysis, the foregoing 40 will so fully reveal the gist of this invention that others can by applying current knowledge readily adapt it for various applications without omitting certain features that, from the standpoint of the prior art, fairly 45 constitute essential characteristics of the generic or specific aspects of this invention, and therefore such adaptations should and are intended to be comprehended within the meaning and range of equivalency of 50 the following claims.

I claim—

1. In a slack adjuster, in combination, a live lever, a dead lever, a telescopic push rod connecting said levers, brake beams and 55 struts associated with said levers, a temporary take up and holding means connecting the brake beams comprising a relatively flat rod having a lost motion slot at one end and a yielding friction clamp device at its other end.

2. In a slack adjuster, in combination, a live lever, a dead lever, a telescopic push rod connecting said levers, brake beams and struts associated with said levers, a temporary take up and holding means con- 60 65

nnecting the brake beams comprising a relatively flat rod having a lost motion slot at one end and a yielding friction clamp device at its other end, and a return spring connecting the central part of the live lever with the brake beam associated with the dead lever. 70

3. In a slack adjuster, in combination, a live lever, a dead lever, a telescopic push rod connecting said levers, brake beams and struts associated with said levers, a temporary take up and holding means connecting the brake beams comprising a relatively flat rod having a lost motion slot at one end and a yielding friction clamp device at its other, the points of connection between said adjusting rod and the brake beams including a ball and socket joint adapted to permit relative turning movement of said rod. 75 80 85

4. In a slack adjuster, in combination, a live lever, a dead lever at opposite sides of the truck bolster, a two part extensible push rod connecting the ends of said levers having a positive permanent take up and holding device co-operating between the effective ends thereof, brake beams and struts associated with the respective levers, an adjusting rod connecting said brake beams having a lost motion slot at one end adapted to provide for brake shoe clearance, a yielding friction clamp at the other end adapted to temporarily take up the excess travel, ball and socket connections between the adjusting rod and the brake beams, and a return spring for restoring the parts to normal position intermediate of one of the brake beams and the live lever. 90 95 100

5. In a slack adjuster, in combination, a live lever, a dead lever at opposite sides of the truck bolster, a two part extensible push rod connecting the ends of said levers having a positive permanent take up and holding device co-operating between the effective ends thereof, brake beams and struts associated with the respective levers, an adjusting rod connecting said brake beams having a lost motion slot at one end adapted to provide for brake shoe clearance, and a yielding friction clamp at the other end adapted to temporarily take up the excess travel. 105 110 115

6. In a slack adjuster, in combination, a live lever, a telescopic push rod having means adapted to permanently take up and hold the excess travel and an adjusting rod associated with one of said parts and having a universal joint connection at one of its points of support. 120

7. In a slack adjuster, in combination, a lever, permanent take up and holding mechanism associated with said lever and temporary take up and holding mechanism adapted to actuate the former on release of the brakes, said last named mechanism including an adjusting rod having a yielding 125 130

frictional clamp at one end mounted to permit universal movement of said adjusting rod.

8. In a slack adjuster, in combination, a truck frame, hangers mounted thereon, brake beams and struts carried by said hangers, live and dead levers associated with said beams, a two-part telescopic push rod connecting said levers having spring actuated friction dogs for positively holding the excess slack and an adjusting rod connecting the brake beams for temporarily taking up the excess travel.

9. In a slack adjuster, in combination, a truck frame, hangers mounted thereon, brake beams and struts carried by said hangers, live and dead levers associated with said beams, a two-part telescopic push rod connecting said levers having spring actuated friction dogs for positively holding the excess slack and an adjusting rod connecting the brake beams for temporarily taking up the excess travel, said adjusting rod comprising a relatively flat member having slots near its ends, one of which slots is adapted to provide predetermined brake shoe clear-

ance while the other permits a temporary taking up of the excess travel of the brake rigging.

10. In a slack adjuster, in combination, a live lever, a telescopic push rod having means adapted to permanently take up and hold the excess travel, an adjusting rod associated with one of said parts having a universal joint connection at one of its points of support and a spring associated with said universal joint to maintain a desired degree of friction.

11. In a slack adjuster, in combination, a live lever, a telescopic push rod having means adapted to permanently take up and hold the excess travel, an adjusting rod associated with one of said parts having a universal joint connection at one of its points of support, and a spring acting between the live lever and the opposite brake beam adapted to aid in returning the parts to normal position.

Signed at New York in the county of New York and State of New York this 16th day of December A. D. 1915.

WILLIAM H. SAUVAGE.
